UNITED STATES PATENT OFFICE.

THOMAS BRINING, OF LEEDS, ENGLAND.

LAST FOR BOOTS OR SHOES.

SPECIFICATION forming part of Letters Patent No. 594,933, dated December 7, 1897.

Application filed September 14, 1896. Serial No. 605,764. (No model.) Patented in England January 12, 1895, No. 795.

To all whom it may concern:

Be it known that I, THOMAS BRINING, a subject of the Queen of Great Britain, residing at Leeds, in the county of York, England, 5 have invented new and useful Improvements in or Relating to Lasts for Use in the Manufacture of Boots or Shoes, (for which I have obtained a patent in Great Britain, No. 795, bearing date January 12, 1895,) of which the 10 following is a specification.

This invention relates to improvements in that class of lasts for use in the manufacture of boots or shoes in which the heel and toe pieces are divided. Hitherto many attempts 15 have been made, with more or less success, to secure the separate parts of a so-divided last firmly together, so that when the said parts are put together and placed within the boot or shoe they will be rigid and even for hammering, lasting, and other purposes. Great difficulty has also been experienced either in securing or locking the parts together or in releasing them when placed inside of the boot or shoe, pokers or other releasing-tools having to 20 be employed for separating the parts, thereby 25 pulling the boot or shoe out of form.

Now the object of the present invention is to construct a divided last so as to be easily and firmly put together, yet readily released 30 and its parts removed from the boot or shoe without stretching or displacing the "upper" and without using a poker or releasing-tool.

The present invention may be applied to an iron last; and it consists, essentially, in 35 combining one or more dovetails and single or double interlocking catches or hooks with a last, divided at such an angle that in separating and releasing, say the toe portion from the heel part, the former is caused to slide 40 toward the heel—that is, within its total length—thereby preventing the stretching of the upper, a spring pin or bolt, hereinafter termed a "spring-pin," being employed for the purpose of preventing the two parts from 45 sliding apart.

In the drawings hereunto annexed, Figure 1 is a part sectional elevation showing the invention applied to an iron last; Fig. 2, a plan of same, looking at the top; Fig. 3, a 50 part plan of same, looking at the bottom; Fig. 4, a part side elevation of the toe portion of an iron last with this invention applied;

Fig. 5, an end elevation of Fig. 4; Fig. 6, a side elevation of the heel portion of an iron last with this invention applied; Fig. 7, an 55 end elevation of Fig. 6.

According to this invention the last is divided, so far as this invention is concerned, into two parts—that is to say, into a toe portion A and a heel portion B; but, if desired, 60 the instep portion of the last may also be made loose, but in the drawings it is shown cast onto the toe portion A. The last may be divided into the two portions A and B at any suitable angle or angles, and I have found 65 by experiment that an angle such as, say, from about forty to about fifty or fifty-five degrees is the most convenient. The line xx which divides the last into two portions is not made in one straight line entirely through the 70 last. In the drawings at Fig. 1 the line xx is drawn at two different angles to form a catch or hook C on each portion of the last and hereinafter termed a "hook"—that is, the lower portion of the line xx from the sole up 75 to the hook is drawn at about an angle of forty-one degrees and from the hook to the top of the last at about an angle of forty-seven degrees; but I wish it to be understood that I do not confine myself to these exact degrees, as they 80 may be varied. By this means the hook C is strengthened; but, if desired, the two portions of the line may be drawn at the same angle parallel to each other, or the line xx may be carried straight through the last at one angle, 85 in which case the hooks C would require to be screwed or otherwise fixed to the toe and heel portions. The hook C on the heel portion B should be notched in the form of a V, as shown at P, to fit a corresponding 90 projection P' on the toe portion A for preventing any lateral movement at the upper part of the said two portions. A dovetailed recess D, having V sides in cross-section, as shown at Fig. 3, is also cast or otherwise 95 formed in the toe portion A, into which the projecting dovetail D' on the heel portion B passes, care being taken that this part of the engagement only extends far enough to hold the parts securely when locked; otherwise 100 jamming will be experienced in removing the last or in relasting. When the heel portion B and the toe portion A are interlocked together by the hooks C and dovetail projec-

tion D', they are so firmly held together that no lateral or endwise movement of the parts can take place; but in order to prevent the two parts A and B sliding apart—say when 5 the lasting operation is being performed as well as when the lasted boot or shoe is taken off the last stand or pivot—a vertical (or nearly so) hole E is bored or cast through the toe portion A at, say, about, or nearly so, a 10 right angle to the sole of the last, and the vertical hole E is carried some distance into the heel portion B, as shown at Figs. 1 and 6. The vertical hole E is preferably, though not necessarily, made of two diameters. Into 15 the vertical hole E is passed a pin F, encircled by a helical spring F', these two parts being hereinafter termed the "spring" pin or bolt F, so that its end will pass into the portion of the vertical hole E, located in the 20 heel portion B. The spring pin or bolt F is arranged to project beyond the top of the last, as shown, and its opposite end may be withdrawn from engagement with the heel portion B by any convenient arrangement or 25 device—such as, say, for instance, by a knob or head F' (shown in dotted lines at Fig. 4) or by a cord passed through the hole F², (also shown in dotted lines at Fig. 4,) or by means of the device shown in the drawings, in which 30 the spring-pin F is armed at its upper end with the projection G and so arranged that its under surface g acts upon a cam-path a, cast, cut, or otherwise formed in or on the toe portion A. The projection G is passed 35 through the hole H, cast or formed in the toe portion A, and which is made to communicate with the vertical hole E. When the projection G is passed through the hole H and turned at, say, a right angle thereto, it per- 40 forms the double function of, first, preventing the spring-pin F working out of position, and, secondly, of withdrawing the said spring-pin

from engagement with the heel portion B when pulled or rotated on the cam-path a.

I is a hole formed in the last for the reception of the last stand or pivot.

To remove the divided last from the boot or shoe, the spring-pin F is first withdrawn, as hereinbefore described, from its engagement with the heel portion B, and as soon as 50 the heel part of the lasted boot or shoe is raised the two portions A and B of the last will readily and easily slide apart without stretching the upper and without using a poker or releasing-tool for separating the two 55 parts of the last.

Having now described the nature of my invention, what I claim, and desire to secure by Letters Patent, is—

In a boot or shoe last divided in an angular and interposed hooked direction, the combination therewith of a projecting dovetail D' on the heel portion, and a recess D on the toe portion with which the said dovetail engages, said dovetail and recess being arranged along the division-line for a part of the distance from the sole to the hook portion thereof, a V-shaped projection P' formed in the recess of the hook of the toe portion A, a recess P in the projection of the hook on 70 the heel portion B with which projection P' engages, a vertical spring-pin F armed with a cam-piece G for locking the two parts of the last together, and a cam-path a formed on the toe portion A and on which the said piece operates, all arranged substantially as herein set forth.

In testimony whereof, I have hereunto signed my name to this specification in presence of two subscribing witnesses.

THOMAS BRINING.
